CLAIM

The ornamental design for a golf putter head, as shown and described.

DESCRIPTION

FIG. 1 is a perspective view of the golf putter head;

FIG. 2 is a top plan view of the golf putter head;

FIG. 3 is a front view of the golf putter head;

FIG. 4 is a right side elevation of the golf putter head, the left side elevation being the same;

FIG. 5 is a rear view of the golf putter head; and,

FIG. 6 is a bottom view of the golf putter head.

The broken line showing of a fragmented shaft on FIGS. 2 and 3 is for illustrative purposes only and forms no part of the claimed design.
